UNITED STATES PATENT OFFICE.

LEO A. HENTER, OF HOT SPRINGS, MONTANA, ASSIGNOR TO NU-COMB MANUFACTURING COMPANY, OF HOT SPRINGS, MONTANA, A CORPORATION OF MONTANA.

COMB.

Application filed March 1, 1923. Serial No. 622,142.

To all whom it may concern:

Be it known that I, LEO A. HENTER, a citizen of the United States, residing at Hot Springs, in the county of Sanders and 5 State of Montana, have invented certain new and useful Improvements in Combs, of which the following is a specification.

This invention relates to improvements in combs, embodying means to facilitate their 10 attachment to the apparel of a person whereby they may be most conveniently and accessibly carried about.

The primary object of the invention is the provision of a vest pocket comb embodying an attaching clip secured thereto in such manner that the comb may be attached or removed with respect to the apparel of a person in the most facile manner, and so that the teeth of the comb will not 20 interfere with the apparel.

Other objects and advantages of this invention will be apparent during the course of the following detailed description.

In the accompanying drawing, forming 25 a part of this specification, and wherein similar reference characters designate corresponding parts throughout the several views.

Figure 1 is a side elevation of a comb, 30 showing the same enlarged and having a novel type of attaching clip secured thereto in improved manner.

Figure 2 is an edge elevation of the improved comb.

35 Figure 3 is a cross sectional view, taken substantially on the line 3—3 of Figure 2.

In the drawing, wherein for the purpose of illustration is shown but the preferred embodiment of this invention, the letter A 40 generally designates the improved comb, having the attaching clip B secured thereto. The comb A may be made of any suitable material, such as ivory, aluminum, hard rubber, pyroxylin, or the like, including a 45 supporting back 10 having teeth 11 extending therefrom in a common plane. The back 10 preferably has the side to which the clip B is attached provided with a convex rib or bulge 12, which may extend longitudinally of the supporting back 10, and which extends laterally of the plane in which the teeth 11 lie. The rib 12, however, need not extend laterally of the plane of the teeth 11 for the entire distance of 55 the supporting back 10, but is chiefly use-

ful in this type of comb for supporting the attaching clip B so that the same cooperates upon the comb A laterally of the plane of the teeth 11. A convenient method of forming the supporting back 10 is that 60 of providing the same of oval shape in cross section, so that both sides thereof extend in convex manner from the sides of the plane of the comb teeth 11.

Referring to the attaching clip B, it is 65 preferred that the same is attached at one end of the comb back 10, having a relatively wide concavo-convex attaching portion 20, which may be secured by a pair of rivets 21 longitudinally of the comb back 10, and upon 70 the convex laterally extending rib 12 thereof. The attaching clip B also includes the tongue 25 which is disposed in spaced relation with respect to the convex rib 12, extending longitudinally of the same and converging 75 to the free end thereof, and upon which free end a ball 26 is preferably provided, normally urged by the resiliency of the tongue 25 into engagement with the crown of the convex rib 12. As is illustrated in Figure 3 80 of the drawing, it can be seen that the ball 26 engages the crown of the rib 12 at a point which is lateral of the plane in which the comb teeth 11 lie.

The application of the comb to the apparel 85 of a person, such as the flap of the vest pocket, is apparent. Inasmuch as the attaching clip has the free end thereof engaging the comb rib 12 at a point laterally of the plane of the comb teeth 11, it can be 90 readily understood that attachment or detachment of the comb A with respect to the pocket flap or apparel of a person's clothing is facilitated, because the teeth 11 will not be urged into engagement with the 95 vest pocket flap or apparel of the person. This arrangement of the clip B and convex rib 12 is highly desirable not only eliminating wear upon the fabric, which would result if the free ends of the teeth of the comb 100 were successively rubbed against the fabric, in saw fashion, so to speak, but also the operation of placing and removing the comb with respect to the pocket is greatly facilitated, the user finding it possible to manipulate the fabric of the pocket so that the comb engages the fabric only along the rib 12, and the teeth 11 are hence not flexed or sprung in such placing and removal of the comb.

Various changes in the shape, size and arrangement of parts, may be made to the form of the invention herein shown or described, without departing from the spirit 5 of the invention or the scope of the claims.

I claim:

The combination with a vest pocket comb having a back portion thereof provided with a convex rib extending laterally of the plane 10 of the teeth of said comb and longitudinally

of the said back portion, of a clip comprising an attaching portion secured to said back portion and within the longitudinal margins of said rib, a resilient tongue extending from said attaching portion longitudinally 15 of said rib, and a ball at the free end of said tongue normally engaging the crown of said convex rib.

LEO A. HENTER.
